PEN AND PENCIL COMBINATION

Harold F. Bajusz, 379 Innes Road,
Woodridge, N.J. 07075

Filed May 14, 1971, Ser. No. 143,730

Term of patent 14 years

Int. Cl. D19—06

U.S. Cl. D74—17 B

FIG. 1 is a front elevation of a pen and pencil combination showing my new design as it appears with the cap covering the pen portion;

FIG. 2 is a side elevation thereof as it appears with the cap removed therefrom;

FIG. 3 is a front elevation view thereof as it appears with the cap covering the pencil portion;

FIG. 4 is a top plan view of FIG. 1;

FIG. 5 is a bottom plan view of FIG. 1;

FIG. 6 is a top plan view of FIG. 3; and

FIG. 7 is a bottom plan view of FIG. 3.

I claim:

The ornamental design for a pen and pencil combination, as shown.
